UNITED STATES PATENT OFFICE

TADAO TACHI, OF HONOLULU, TERRITORY OF HAWAII, ASSIGNOR TO HAWAIIAN PINEAPPLE COMPANY, LIMITED, OF HONOLULU, HAWAII, A CORPORATION OF HAWAII

FRUIT CUTTING MACHINE

Application filed February 15, 1932. Serial No. 593,152.

The invention relates to a machine for cutting slices of fruits, such, for example, as pineapples, into half slices and is especially adapted to the treatment of damaged or imperfect slices from which half slices may be cut, the initial slices being assembled in parallel relation in a trough with the good portions of the respective slices disposed within the trough, then cutting off the portions 10 of the slices projecting beyond the upper edges of the trough by means of a reciprocating knife moving longitudinally of and parallel with said upper edges, the trough being pivoted at one end and held in operative 15 position by a latch engaging the other end, whereby, when the latch is tripped, the trough will swing downwardly and discharge the severed half slices, preferably into cans or other containers which are supported in 20 proper position on the machine to receive the half slices.

The invention is illustrated in the accompanying drawings, in which:—

- Fig. 1 is a side elevation.
- Fig. 2 is a front elevation.
- Fig. 3 is a longitudinal section on line 3—3 of Fig. 2.
- Fig. 4 is a section on line 4—4 of Fig. 3.
- Fig. 5 is a fragmentary view looking in 30 the direction of the arrow in Fig. 1.
- Fig. 6 is a plan view of the knife.
- Figs. 7 and 8 are detailed views of the spring motor.
- Fig. 9 is a fragmentary perspective of a 35 filler piece for operating on slices of smaller diameter.

Figs. 10 and 11 are plan and edge views, respectively, of a damaged slice, before cutting.

Referring to the drawings, 1 indicates a 40 bracket-like casting having a flat top or table section adapted to support a can or other receptacle in which the product is to be packed, said bracket having a clamp 2 adapted to engage a perpendicular flange on a packing table with which the machine is to be associated. Bolted to the bracket 1 are two parallel side frame members preferably formed of channel bars, each member comprising a 45 lower perpendicular section 3 and a rearwardly inclined section 3', the sections 3 and

3' being secured together by flat plates or gussets and the two side members being connected adjacent the bends or angles by a cross member 4, which also constitutes an abutment for the stack of slices assembled in the 55 machine.

Each of the inclined sections 3' of the side members has secured to its inner face a batten or strip 5, which is provided with a longitudinal groove in its inner face serving as a 60 guide for the knife. Attached to the upper faces of the strips or battens 5 are upwardly and outwardly inclined guard strips 6, which extend longitudinally of the side members from the lower ends thereof to points short 65 of the upper ends. Pivoted by cross pin 11 carried by the upper side members 3', is a generally semi-cylindrical trough 10, the lower end of which normally lies adjacent the abutment 4 and is held in such position by means 70 of a spring bolt 12 slidably mounted on the lower face of the abutment 4, provided with an operating hand piece 12'.

Pivoted to bearing blocks 16 secured to the frame members 3' is a swinging bail 15, 75 which embraces the trough and serves to swing the latter into normal position to be engaged by the latch 12 and to limit the outward swinging movement of the trough, when the latter is released, said bail preferably 80 being provided with extensions 15' on either side of the machine by means of which the bail may be operated to swing the trough into closed position, as indicated more particularly in Figs. 1 and 3.

Mounted between the side members 3' and 85 slide longitudinally thereof is a flat knife 20 mounted on a support 21, the lateral edges of which engage the grooves in the battens 5, 5 to guide the knife parallel with and in close proximity to the upper edges of the trough 10, as indicated in Fig. 4. The said support is provided with upturned ears 22 between which is secured a handle 23 and the front or lower portion of the support is bent 90 upward and backward to form a shield 24 having undercut sides to overhang the guard strips 6, 6, the shields serving to force the upper portions of the cut fruit to the point of ultimate discharge.

Mounted on face plates 25, 25 spanning the upper ends of the side members 3' is a spring motor 26, which may be of any approved type and which is conventionally illustrated in 5 Figs. 7 and 8, adapted to automatically wind up the cable 27, one end of which is attached to the support 22, said spring motor serving to retract or return the knife and its support to the upper or inoperative position, as indicated 10 in full lines in Figs. 1 and 3.

To adapt the machine for cutting slices or disks of smaller diameters, there is preferably provided one or more attachments or filler blocks of the character indicated at 30 in 15 Fig. 9. These may be of an external diameter adapted to fit the interior contour of the trough 10 and an inner diameter to accommodate the curvature of the particular slices to be cut, the selected filler being secured to the 20 inner face of the trough by clamps, screws or any other appropriate means.

The operation of the machine is as follows: The machine is mounted on the feed table in the relation indicated in Fig. 1, so that the 25 attendant may select the damaged or imperfect slices passing over the feed table and stack the selected slices in edgewise relation in the trough 10 with the unimpaired portions of the slices lying within the body of the 30 trough and the damaged or impaired portions extending above the edges of the trough. When a sufficient number of slices have been thus assembled in the trough, the operator moves the knife 20 downward by means of 35 the handle 23, against the tension of the spring drum 26, thereby cutting off the projecting tops or upper portions of the slices, leaving the series of perfect half slices in the trough and ultimately forcing the severed 40 upper portions of the slices off the lower end of the machine onto the belt or other conveyor usually associated with the packing table, by which the severed portions are delivered to the apparatus employed for converting the 45 same into crushed fruit. After the cutting operation has been completed, by the movement of the knife throughout the entire length of the trough, the operator releases 50 the knife, which is immediately returned to the inoperative position by the spring motor 26. The operator then actuates the latch 12, which releases the lower end of the trough, thereby permitting the trough to swing outward and discharge the half slices therein 55 into a can or other receptacle mounted on the bracket 1, as indicated in Fig. 1, the outward movement of the trough being limited by the bail 15. When the cut half slices have 60 been discharged from the trough, the latter is swung back into normal position by the operator swinging the bail 15 by either handle 15' until the lower end of the trough snaps behind the nose of the latch 12 and the machine is then in condition to receive the next 65 batch of imperfect or damaged slices to be cut

into half slices by the succeeding operation of the knife.

What I claim is:

1. A machine for cutting slices of fruit into half slices, comprising a supporting frame including spaced parallel side members, a trough pivoted at one end to the frame for swinging movement and adapted to receive the fruit slices in edgewise relation, a knife mounted for sliding movement in and longitudinally of said side members and over said trough, and means for releasably holding the opposite end of the trough. 70

2. A machine for cutting slices of fruit into half slices, comprising a supporting frame including perpendicular and rearwardly inclined side members, a trough pivoted at its upper end between the inclined portions of the side members and adapted to receive the fruit slices in edgewise relation, 80 a knife slideable longitudinally of and between the said inclined portions adjacent the upper edges of the trough, and means for releasably holding the opposite end of the trough. 85

3. A machine for cutting slices of fruit into half slices, comprising a supporting frame including a base bracket for holding a receptacle and perpendicular and rearwardly extending parallel side members, a trough pivoted at its upper end between the inclined portions of the side members and adapted to receive the fruit slices in edgewise relation, a knife slideable longitudinally of and between the said inclined portions adjacent the upper edges of the trough, and means for releasably holding the opposite end of the trough. 90 95

4. A machine for cutting slices of fruit into half slices, comprising a bracket including a clamp for attaching the machine to a packing table and a shelf for holding a receptacle, parallel side members secured to the bracket each having a perpendicular and a rearwardly inclined section, a trough pivoted at its upper end between the inclined sections and adapted to receive the fruit slices in edgewise relation, a knife slidably mounted between the inclined sections in parallelism with the upper edges of the trough, and a latch for releasably engaging the lower end of the trough. 100 110 115

5. A machine as described in claim 4, including a spring motor for retracting the knife. 120

6. A machine for cutting slices of fruit into half slices, comprising a bracket including a clamp for attaching the machine to a packing table and a shelf for holding a receptacle, parallel side members secured to the bracket each having a perpendicular and a rearwardly inclined section, an abutment between the lower ends of the inclined sections, a trough pivoted at its upper end between the inclined sections and adapted to receive 125 130

the fruit slices in edgewise relation, a knife slidably mounted between the inclined sections in parallelism with the upper edges of the trough, and a latch for releasably engaging the lower end of the trough.

7. A machine as described in claim 1, provided with means for automatically retracting the knife after each cutting operation.

8. A machine as described in claim 1, including a spring motor mounted on the upper end of the frame and connected to the knife for retracting the latter after each cutting operation.

9. A machine as described in claim 4, in which the knife is provided with an operating handle and a shield in front of the latter.

10. A machine for cutting slices of fruit into half slices, comprising a bracket including a clamp for attaching the machine to a packing table and a shelf for holding a receptacle, parallel side members secured to the bracket each having a perpendicular and a rearwardly inclined section, a trough pivoted at its upper end between the inclined sections and adapted to receive the fruit slicer in edgewise relation, a knife slidably mounted between the inclined sections in parallelism with the upper edges of the trough, a latch for releasably engaging the lower end of the trough, a shield secured to and movable with the knife, and guard wings on the inclined sections cooperating with the shield to discharge the upper portions of the cut slices.

35 In testimony whereof I affix my signature.
TADAO TACHI.
